(57) **CLAIM**

I claim the ornamental design for an electronic cigarette, as shown and described.

DESCRIPTION

FIG. 1 is a front elevational view of an electronic cigarette showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front, right, and top perspective view thereof; and,
FIG. 8 is a rear, left, and bottom perspective view thereof. The broken lines immediately adjacent shaded areas define the bounds of the claimed design and form no part thereof. All other broken lines in the figures are included for the purpose of illustrating portions of the electronic cigarette which form no part of the claimed design.
